By his Attorney, *William D. Wilkes*
W. B. Hutchinson.

UNITED STATES PATENT OFFICE.

WILLIAM D. WILKES, OF BROOKLYN, NEW YORK, ASSIGNOR TO PAXFLAT BARREL & CRATE CORPORATION, A CORPORATION OF NEW YORK.

HOOP FASTENING.

Application filed April 9, 1926. Serial No. 100,857.

My invention relates to improvements in hoop fastenings, and the object of my invention is to produce a cheap, strong, simple fastening which can be readily applied to a barrel or other package, which will lie flat upon the package, and which will hold the hoop firmly without loosening. My invention is especially intended to produce a hoop fastening which can be easily operated, will lie, as stated, perfectly flat upon the package, and which can be opened up manually with ease, to the end that the fastening may be repeatedly used. This is a decided advantage because in many cases these fastenings necessitate the destruction of either the hoop or fastening in freeing them. My invention is further intended to produce a simple structure in which the pressure against the hoop and the tension of the latter will serve to bind some of the parts firmly in place.

Reference is to be had to the accompanying drawings forming a part of this specification, in which similar reference characters indicate corresponding parts in all the views.

Figure 1 is a broken outside face view of the fastening as complete with both hoop ends secured.

Figure 2 is a section on the line 2--2 of Figure 1.

Figure 3 is an inside elevation of the complete fastening, and

Figure 4 is a detail of the fastening blank.

In my fastening I use a plain blank 10 which is preferably somewhat elongated so that when applied it will lie beneath or behind the hoop, and the pressure of the latter will serve to hold the fastening straight and in place. The blank is provided near one end with opposed ears 11 and 12 which are arranged in pairs and spaced apart. The ears as shown protrude from opposite edges, and the blank is made of ordinary bendable sheet metal, to the end that the ears may be turned inward at the proper time. The blank is provided with a transverse slot 13 which is of a length to receive the full width of the hoop 14, and to this end the slot is made opposite the two ears 11 so as not to weaken the fastening, and as the metal of the ears comes opposite the slot ends the fastening is sufficiently strong.

In applying the fastening, one end of the hoop 14, to wit, the end 14', is laid over the face of the blank 10, lying between the ears

12, and is thrust through the slot 13 and turned under as shown clearly in Figure 2, so that the simple looping of this end of the hoop is ample to hold it firmly in place because when the fastening is tightened the pressure of the package and tension of the hoop causes the end 14' to be bound positively between the package to which it is applied and the blank 10. After this is done, the hoop 14 is passed around the package, and the second end 14' drawn with a suitable tightening instrument firmly over the face of the blank 10 and between both ears 11 and 12. While the tension is thus maintained, the ears 12 are folded in upon the 70 hoop and thus overlap the second hoop end as shown clearly in Figure 2, and the second end portion 14' is turned back over the ears 12 which thus act as a fulcrum to provide for the bending of the hoop while still under 75 tension. The end part 14'' is laid flat upon the body portion 14 of the hoop, as the drawings clearly show, after which the ears 11 are folded in and pressed firmly down upon the end 14''. Thus the fastening can be 80 easily applied, and it will be noticed that the end 14' is bound firmly between the blank 10 and the package, while the end 14'' is held by both ears 12 and 11, the ears 12 serving as stated as a fulcrum, and the ears 11 holding the free end 14'' firmly and flatly in place.

Thus a secure fastening is made, and it will be seen that when the fastening is to be unfastened, one can easily turn up the ears 90 11, thus freeing the end 14'', and then the ears 12 can be likewise turned up so that the end 14'' will be entirely released and the hoop will be free.

I claim:—

1. A hoop fastener, comprising a blank forming a body having pairs of opposed ears at opposite edges, said ears overlying one face of the body and their pairs being in different planes, whereby one hoop end can be 100 trained in loop formation over and under the respective pairs of ears and held fast thereby, said body being formed with a slot underlying one pair of ears and of a size to receive the other hoop end with a portion of 105 the same beneath the first named hoop end and said pairs of ears and another portion trained back to lie against the other face of the body.

2. A hoop fastener, comprising a blank 110

forming a body having pairs of opposed ears at opposite edges, said ears overlying one face of the body and their pairs being in different planes, whereby one hoop end can be trained in loop formation over and under the respective pairs of ears and held fast thereby, said body being formed with a slot underlying one pair of ears and of a size to receive the other hoop end with a portion of
10 the same beneath the first named hoop end

and said pairs of ears and another portion trained back to lie against the other face of the body, and an extension on the body at one end thereof forming a continuation of said body.

In testimony whereof, I have signed my name to this specification this 31st day of March, 1926.

WILLIAM D. WILKES.
